[57] CLAIM

The ornamental design for a resuscitator for administering CPR, as shown and described.

DESCRIPTION

FIG. 1 is a front perspective view of a resuscitator for administering CPR showing our new design;

FIG. 2 is a rear perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof; and,

FIG. 8 is a right side elevational view thereof.

The broken line showing of a head strap in FIG. 1 is for illustrative purposes only and forms no part of the claimed design.
